Claims priority, application Switzerland Jan. 29, 1960

1 Claim. (Cl. 102—52)

This invention concerns a fuse intended primarily for use in hollow charge projectiles.

The fuses heretofore proposed for use in hollow charge projectiles can be divided into three distinct categories, namely inertia base fuses, fuses functioning by compression (possibly by compression and inertia) and electric fuses.

Inertia base fuses are, in general, only slightly sensitive and have, at impact, an appreciable delay in firing, especially at large firing incidences, since they necessitate the braking or the stopping of the entire mass of the projectile before percussion. Attempts have been made to remedy these disadvantages by reinforcement of the strength of the cap and of the body of the projectile which supports it with a view to reducing deformation of the projectile at impact and the delay in the functioning by inertia, but these arrangements involve an appreciable increase in weight with the disadvantages which relate thereto.

Percussive fuses, which function by compression, or by compression and inertia, avoid, to a large extent, the aforementioned defects and can comprise very light plungers provided with a hard head of small size allowing the instantaneous functioning against armor-plating, even at large firing incidences.

It can happen, however, that the projectile touches the target at a peripheral point on its cap without there being contact and compression of the plunger. The danger of non-functioning is increased by the new defenses discovered for combat vehicles with a view to causing the dislocation of the hollow charge projectile; braking, stopping or non-functioning can also result on obstacles such as grilling, pins, indentations, and the like, without the plunger of the fuse being either compressed or actuated by inertia where the latter is provided.

Hence it has been proposed to provide hollow charge projectiles with electric fuses which actuate a detonator on impact. But devices of this type are complex, costly, and difficult to construct. Furthermore, they require movable contacts and insulation, defects of which can often be the cause of failure to function, so that it is generally necessary to add electro-mechanical safety devices which make them heavy and cumbersome.

The present invention has for its object to remedy the aforementioned disadvantages. According to the invention there is provided a fuse primarily intended for use in a hollow charge projectile and positioned in front of a charge, wherein the fuse comprises at least one percussive device and firing elements and wherein the percussive device comprises a peripheral collar of a diameter near to that of the projectile and having at its front an edge harder than current armor-plating, said collar being fixed on a rigid support of which the central part is adapted to control the action of one of the firing elements on impact of the projectile against a target.

By this means a fuse may be constructed of which the percussive device constitutes an assembly of mass small with respect to that of the projectile, this assembly being arranged so that on the impact of the projectile and up to a very large angle of impact, even on a target of great hardness, the peripheral collar can dig itself into, be stopped momentarily by and not slide on the target, and

2

is capable of causing, at the center of the percussive device, a relative movement assuring the functioning of a detonator fuse and consequently the transmission of the firing to a principal detonator for the explosive charge.

Preferably, the peripheral collar of the fuse is constituted by a band of case-hardened steel, and can be force-fitted, screwed, glued or set in a housing of the percussive device.

The percussive device is retained annularly by at least one element deformable or shearable on impact so that only this device is stopped on the target, the principal mass of the projectile maintaining its speed until percussion.

In a particular embodiment of the invention, there can be added a system fused by a relay-detonator fixed axially on a support integral with the projectile but independent of the detonating fuse and the percussive device. It results from this arrangement that, on impact, even if the detonating fuse is thrust obliquely by the relative movement of the percussive device, the transmission of the firing emanating from the relay-detonator remains centered along the axis of the projectile.

A ballistic cap, formed in one or several parts of a generally cylindro-ogival form, acts as an annular support for the percussive device. This cap assures the protection of the fuse in case of fall in the course of transportation and handling as well as its complete sealing.

Preferably, an annular setting of the cap, possibly in zones or at points, retains the percussive device in position; this setting can constitute, by itself, the deformable element which gives way on impact of the peripheral collar on the target.

In one modification, the element deformable on impact is an envelope with a generally cylindrical form which is fixed in front of the hollow charge and which has a series of annular corrugations.

The fuse may be completely housed in a cylindrical part of a ballistic housing arranged on the front of the projectile so that the ogival nose contributes to the safety in falling and a deformation of this, even a substantial one, does not cause percussion. The ogival nose constitutes at the same time, as shown by tests, a safety chamber the wall of which does not give way, under the force of an unforeseen shock, to untimely functioning of the detonating fuse. This characteristic, added to the fact that the hollow charge projectile can comprise a supplementary safety device arranged behind the summit of the perforation cone, prevents bursting of the cap from reaching the firer or the gun crew, as would be possible in the absence of this arrangement.

The percussive device may be made independent from the firing elements so that the direction of displacement on impact of this device does not affect the axial movement of the plunger, the point of which remains directed towards the center of the fuse. To this end, the plunger and the fuse-cap can be mounted at the top of a rigid support independent from the percussive device. If the projectile hits the target at a large angle of incidence, the percussive device tends to begin a movement of rotation about a point diametrically opposite to that of the impact and constitutes a lever the central part of which acts, in the manner of a push rod, on the plunger. The latter, guided and centered in the plunger gate is only actuated by the axial component of the displacement of the percussive device.

With a view of reducing as much as possible the transverse component of the movement of the percussive device, the central part of the latter is arranged at a very small distance (1 to 2 millimetres) from the head of the plunger.

However, the plunger and the fuse-cap may, on the contrary, be integral with the percussive devices, only a spacing member of synthetic plastic or elastic material retaining the detonating fuse at a suitable distance from the point of the plunger. This arrangement gives the fuse a high sensitivity, since on impact it can function at the same time by compression and by inertia of the detonating fuse which falls on the plunger. The relay-detonator assures the axial transmission of the firing to the principal detonator.

The fuse of the present invention functions when the projectile touches the target at any point whatsoever of its ogival cap and this even at a very large angle of incidence of impact. This characteristic results from the fact that the percussive device has a diameter near to that of the projectile, and from the fact that it is designed to bite momentarily into the target, thus to stay there fixed and stopped without sliding or rebounding. Moreover, the mechanico-pyrotechnic assembly is such that it functions whatever may be the direction of the displacement of the percussive device on impact, with respect to the axis of the projectile, the percussive device necessarily causing, by one of the aforementioned means, the axial transmission of the firing to the principal detonator.

The safety of the fuse in the course of transportation and handling is assured by the ballistic cap which, in the case of the projectile falling on its head, can be deformed for a sufficient distance, without interaction with the percussive device. Furthermore, a safety mechanism with automatic retraction at the start of the shot can be added to said fuse, if so desired.

In another modification, the percussive device instead of being supported by the ballistic cap of the projectile is retained on a supplementary interior cap by an annular flange of small strength which is deformable or shearable on impact. In this arrangement, a small annular space is provided between the percussive device and the ballistic cap so that the latter acts as a protective device for the fuse.

The plunger, which is of very small mass, can be either integral with the percussive device or independent thereof. In the latter case, the plunger is centered and suspended, with regard to the detonating fuse, by at least one element, for example a washer shearable or deformable under the action of the percussive device which, at the impact, knocks against the head of the plunger. Preferably, a peripheral space is provided between the wall of the fuse-cap and the plunger so that during the operation, the latter is not submitted to any rubbing.

In a particular modification, a safety system is incorporated in the fuse, the safety system being retractable at the beginning of the shot and, until then, being interposed between the plunger and the central part of the percussive device.

The safety system can be constituted by an assembly of cylindrical segments housed in an annular inertia block, the said segments being thrust radially towards the exterior by an opposed member, such as a spring or the like. The falling back of the inertia block at the start of the shot causes the lateral drawing aside of the segments under the effect of the member.

As mentioned above, the ballistic cap may surround the percussive fuse, and with a view to increasing as much as possible the incidence of functioning of the percussive device, the cap must at least comprise an annular zone of small thickness and strength in front of the peripheral collar. It results from this that, on impact, the said cap is easily crushed at its point of contact with the target and that the peripheral collar, thus uncovered, bites into the target.

With a view to making the firing elements easily removable, the percussive device can be effectively integral with a case containing the fuse-cap, the said case being engaged in the anterior part of the ballistic cap. If the fuse is further provided with a relay-detonator,

this can be connected to said fuse-cap by a flexible connecting element. It results from these arrangements that by extraction of the said case, it is possible to withdraw the fuse at the same time as the detonator fuse and the relay-detonator.

In order to enable the invention to be more readily understood, reference will now be made to the accompanying drawings, which illustrate diagrammatically and by way of example some embodiments thereof, and in 10 which:

FIG. 1 is an axial section of a hollow charge projectile provided with a fuse,

FIG. 2 shows in axial section part of a modification of the hollow charge projectile shown in FIG. 1,

15 FIG. 3 shows on an enlarged scale and in axial section a detail of FIG. 2,

FIG. 4 shows in axial section a modification of the projectile shown in FIG. 2,

20 FIG. 5 shows in axial section another modification of the projectile shown in FIG. 2,

FIG. 6 shows in axial section a detail of FIG. 5, and

FIGS. 7 to 10 illustrate schematically the functioning of the fuse in the hollow charge projectile.

Referring now to FIG. 1, there is shown a hollow 25 charge projectile comprising an envelope 1, in the interior of which is disposed an explosive charge 2 and a metallic cone 3 lining the cavity of said charge. A support 4 with a generally conical form is fixed at its base 5 on the periphery of the hollow charge, and is provided 30 at its center with a fuse-cap 6 in which there is screwed 35 at 7 a detonating fuse 8. A washer 9, set in the head of the fuse-cap 6, retains a plunger 10 of very small mass, the position of which is at a suitable distance from the detonating fuse, a peripheral space 11 occurring between the plunger 10 and the fuse-cap 6.

The percussive device comprises a plate or support 12, 40 of light metal, which has a diameter close to that of the caliber of the projectile and which has an annular housing in which is force-fitted a peripheral collar 13 which, however, may alternatively be crimped or glued in 45 position. The collar 13, which is made, for example, of case-hardened steel, is provided at the front with an edge 14 intended to bite into the target on impact by incidence.

45 An interior cap 15 concentric with the support 4 supports the percussive device through the intermediary of an annular piece 16 retained by crimping at 17 on the cap 15. Tongues 18, integral with the piece 16 and folded back at a right angle towards the outside, support 50 the percussive device at its base. These deformable tongues 18 of small strength permit, on impact with the target, a relative movement of the percussive device with respect to the principal mass of the projectile and the percussion of the fuse 8 by the plunger 10. The assembly 55 of the fuse shown in FIG. 1 is surrounded by a ballistic cap 20 of small thickness, the rear part of which completely surrounds the fuse and is cylindrical, whilst the forward part of the cap 20 is ogival. The cap 20 can be fixed on the projectile by crimping of the envelope 1 60 at 21. It will be noted moreover that a small annular space is provided between the percussive device 12, 13 and the ballistic cap 20 so that the latter plays the role of a protection member for the fuse.

In the modification shown in FIGS. 2 and 3, the 65 ballistic cap is formed in two parts, an ogival part 22 and a cylindrical part 23, and supports the percussive device. An annular crimping 24 (possibly in zones or at points) of the ogival part 22 in a peripheral groove of a plate 25, retains the percussive device in position. 70 The crimping 24 itself constitutes, in this modification, the deformable element which gives way on impact of the peripheral collar 13 on the target.

The fuse includes a safety system retractable at the 75 start of the shot and, up till then, interposed between a plunger 26 and a central part 27 of the percussive

device. This system is constituted by an assembly of segments 28 housed in an annular inertia block 29 having elastic tongues 30 engaging the segments 28. The segments 28, the bases of which rest on an anterior edge 31 of a fuse-cap 32, are thrust radially towards the exterior by a spring or like member 33. At the start of the shot, the inertia block 29 falls back and its tongues 30 free the segments 28 which are forced aside laterally under the effect of the spring 33 so that the fuse is armed.

In the modification shown in FIG. 4, a plunger 55 and a fuse-cap 56 are mounted on a percussive device comprising a plate or first rigid support 58, and a peripheral collar 57, a spring 59 retaining a detonating fuse or primer 60 at a suitable distance from the plunger. The faces of the active edge of the peripheral collar 57 preferably form an angle of 90°.

On impact, the fuse shown in FIG. 4 can function at one and the same time by compression of the percussive device 57, 58 and by inertia of the primer 60 which falls on the plunger 55. Contrary to the embodiments shown in FIGS. 1 to 3 and 5, the peripheral collar 57 is external to the ogival cap 61 so that it directly contacts the target on impact of the projectile. For this purpose, the support 58 of the percussive device comprises towards the from an annular extension 62 into a groove of which there is set at 63 the base of a cap 61. The element deformable on impact is constituted by a cylindrical envelope 64 which is provided with corrugations 65 and which carries the percussive device 57, 58.

A relay-detoner 66 is fixed axially on a second support 67 mounted on the projectile, but independent from the percussive device 57, 58 of the detonator fuse 60 and the plunger 55. It results from this arrangement that, on impact of the peripheral collar 57 on the target, the transmission of fire emanating from the relay-detoner 66 remains centered along the axis of the projectile, even if the fuse 60 is thrust obliquely by the relative movement of the percussive device 57, 58. A removable hood 64a, for example of plastic material (shown in dot-dash lines in FIG. 4), covers the anterior part of the projectile and provides supplementary protection for the fuse.

FIGS. 5 and 6 show a modification of the fuse shown in FIG. 4, and in this modification the firing members, namely, a plunger 68, a fuse 69 and a relay-detoner 70 are easily removable. To this end, the primer-holder 71 is fixedly secured in one end of a case 72 screwed axially on the percussive device. The case 72, which is open at the front, is engaged in an orifice in a cap 73 and is centered by a rim 74 defining the orifice in the cap. A plug 75, for example of plastic material, blocks the open end of the case 72 and assures the sealing of the fuse. The primer-holder 71 is linked to the relay-detoner 70 through a flexible connecting member 76, fixed at 77 on the primer-holder 71 and at 78 on a collar 79 into which there is screwed the relay-detoner 70.

The collar 79 is fixed and centered in the axial part of a second support 80 of conico-cylindrical form. By unscrewing the case 72, held at 81 on the percussive device, the aforementioned elements of the firing device can be extracted in a single operation. The connecting element 76 is sufficiently flexible and deformable for the relay 70 supported by the support 80 to remain centered and oriented in the axis of the projectile, even if the fuse 69 is thrust obliquely by the impact of the percussive device.

FIG. 6 shows on a larger scale, the fuse-cap 71 in front of which there is set the head of the plunger 68. The detonating fuse 69 is retained in a truncated housing 82 by a spring or spacing element 83 the lower 70 spiral of which bears on the annular rim 84 of a cen-

tering piece engaged at 85 on the fuse or primer 69. The peripheral space between the fuse 69 and the wall of the housing 82 limits rubbing and facilitates the travel of said primer on impact of the projectile.

FIGS. 7, 8, 9 and 10 illustrate schematically the functioning of a fuse according to the invention:

During normal impact (FIG. 7), the cap 92 is crushed and the percussive device 93 is arrested on the target, while the principal mass of the projectile continues its travel and while the fuse 94 falls onto the plunger 95. The functioning of the fuse 94 causes that of the relay 96 and the firing of the principal detonator (not shown) of the hollow charge. If the projectile hits the target at a large angle of incidence (FIG. 8), the peripheral collar, of material harder than current armor-plating, bites at 97 into this target. The eccentricity of the percussive device 93 does not prevent the transmission of fire to relay 96. The latter in fact remains centered along the axis of the projectile, since it is mounted on an independent support which does not undergo any action of the percussive device. The fuse operates equally on the ground, on a soft target (earth, mud, etc.), as shown in FIG. 9 since the mass of the percussive device is very small with respect to that of the projectile and for this reason has a negligible inertia on impact.

On the other hand, the safety of the fuse, in the course of transportation and handling, is assured by the ogival ballistic cap 92 which, in the case of the projectile falling on its head, can be deformed to a sufficient extent (FIG. 10) without interaction with the percussive device. It will be noted that the envelope 98 on which the percussive device is fixed is more resistant than the cap 92 so that only the latter is deformed in the case when the projectile falls onto the ogival cap.

In the embodiments of the invention described above, the fuse is shown in the head of hollow charge projectiles (rifle grenades, or rockets), but it can also be mounted on different projectiles such as anti-personnel grenades, or incendiaries.

What is claimed is:

A fuse mechanism for mounting on the front of a hollow charge projectile, comprising a deformable cylindrical envelope the base of which is mounted on the projectile, a rigid support on the envelope and an ogival cap 45 on said support, said support having a peripheral hardened collar with a diameter approximately that of the envelope, a primer-holder centrally mounted on said support, a truncated housing in said primer-holder, said housing having a narrow base, a primer in said primer-holder, said primer resting on the narrow base of said holder, a plunger rigidly mounted on the primer-holder, a centering piece engaging the top of said primer, a spring 50 between said primer and the wall of said truncated housing, a second support on the projectile within said deformable envelope rearwardly of said first support, a relay-detoner centrally disposed in said second support and a flexible member connecting said primer-holder to said relay-detoner.
